ALWIN TALKE, OF BRESLAU, AND ARTHUR TALKE, OF OBER-LAUSITZ, GERMANY, AS
SIGNORS OF ONE-THIRD TO BERTHA TALKE, OF OBER-LAUSITZ, GERMANY

COUNTERPOISE ATTACHMENT PARTICULARLY FOR CYCLE-PEDALS

Application filed May 7, 1930, Serial No. 450,546, and in Germany December 11, 1929.

This invention refers to special developments in, and methods of fixing counterpoising attachments, particularly for cycle-pedals, for the purpose of maintaining the 5 pedals in a horizontal position as well as for distributing the wear and tear uniformly between both faces of the pedal-tread, without necessitating the release or removal when changing the faces, and without making 10 screw-drivers and the like tools necessary for increasing the tension or for changing over from one face of the tread to the other.

The accompanying drawings elucidate the 15 invention as described in the following specification and claims.

Fig. 1 is an elevation of the fixing clamp in the form of a spiral or helical spring; Fig. 2 a plan of same; Fig. 3 is a side view of a 20 pedal with section of outer frame removed to illustrate the method of attaching the spiral spring clamp and weight to the axle-sleeve; Fig. 4 is a perspective view of the weight with holding devices; Fig. 5 is a side view similar in part to Fig. 3, but with the helical or spiral spring clamp for holding the weight used in 25 reversed arrangement, and Fig. 6 is a perspective view of the weight, with holding devices characterized by projecting letters.

The process of fixing the counterpoise attachment takes place by forcing the ends 30 2 and 3 of the spiral spring clamp (Fig. 1) apart (as shown by arrows in Fig. 2) and over the axle-sleeve 4 (Fig. 3) around which the spring then snaps, and subsequently pushing the weight 5 under the sleeve 4. According 35 to the tension required, the ends 2 and 3 are made to engage in the notches or rests 6, 6, or, as shown in drawings, 7, 7 for example, or in 7 and 8, or, furthermore both 40 only in the rest 8. In some cases it may, of course, be advisable to reverse the position of the clamp 1, so that, as shown in Fig. 5 for example, the bend 9 engages in rest 8 of the weight, whereas the ends 2 and 3 (instead 45 of 9 in Fig. 3) embrace the axle-sleeve. In the latter case the spacing tension between the ends 2 and 3 (as shown by the arrows in Fig. 5) which is exerted in a direction parallel to the axle-sleeve, and is produced by forcing the clamp over the latter, or is previously 50

purposely provided, automatically regulates every tension requirement, including that caused by the insertion of the weight. The projections on the weight may also take the form of letters or characters, as shown in 55 Fig. 6 for example, or may be given any other suitable shape, such as for example, notches, grooves, channels, jags, bosses, hooks, pins, etc.

When, as shown in Fig. 3 for example, the 60 face *a* of the tread has been positively held uppermost in horizontal position and consequently subjected to wear and tear for some time because the counterpoise is situated on the face *b* of the tread, a change can be made, 65 as required, without releasing or removing the device, by simply turning the counterpoise weight 180 degrees around the axle-sleeve, which brings it to face *a*, in which position it positively holds face *b* of the tread uppermost (as shown in Fig. 5) and subjected to 70 equalizing wear and tear. Later on, according to circumstances, the process can be repeated, so that the faces *a* and *b* of the tread are 75 alternately uppermost.

The clamp 1 may also be used in reverse, as shown in Figure 5, wherein the spring 9 is engaged in the notch 8 and the ends 2 and 3 rest on the axle sleeve; this is the reverse of the showing in Figure 3.

To fasten the spring the part 9 is engaged 80 in the notch and the arms 2 and 3 are spread apart and engaged on the axle. In thus spreading the parts 2 and 3 they will be held in a tighter grip, and the weight will come 85 into a settled position, and will bring the counterweight into its last position. In removing to release the parts the springs ends are brought toward each other.

After having thus described the nature and 90 method of employment of our invention, what we claim is:—

1. In a counterpoise device, a weight having a multiplicity of retaining devices, a spiral spring embracing the axle-sleeve of a 95 pedal and the counterpoise weight whereby the parts are held under tension.

2. In a counterpoise attachment, a clamping spring for the axle-sleeve, and means for retaining the weight in position by altering 100

the tension spaces of the windings of the spring.

3. A counterpoise means embodying a clamping spring for a revoluble member, and 5 means cooperable with the said spring for compensating for variations in diameter of the axle sleeve.

4. In a device of the character stated, a weight having projections, in combination 10 with a spring member having arms to cooperate with said projections.

In testimony whereof we hereunto affix our signatures.

ALWIN TALKE.
